UNITED STATES PATENT OFFICE.

ERNEST G. McCUALEY, OF DAYTON, OHIO.

AUTOMATIC LOCKING DEVICE FOR AIRPLANE RUDDER BARS.

Application filed May 13, 1922. Serial No. 560,751.

To all whom it may concern:

Be it known that I, ERNEST G. McCUALEY, a citizen of the United States, residing at Dayton, in the county of Montgomery and State of Ohio, have invented certain new and useful Improvements in Automatic Locking Devices for Airplane Rudder Bars, of which the following is a specification.

This invention relates in general to controlling devices, more particularly constructed for use in aircraft, and more particularly to an improved rudder bar for operating the rudder of said aircraft.

It is the object of this invention to provide a positive and automatic locking arrangement of the foot-controlled rudder bar whereby the rudder control surface may be locked in any desired position, so set by pressing with either foot, the foot control bar, and also to provide a positive release mechanism whereby the rudder may be unlocked from any position thus set.

By having the rudder locked securely in any desired position, both feet of the pilot will be free to be withdrawn from cramped position and available to execute other operations such as the releasing of bombs, pumping of air to gas tanks, controlling of the engine throttle, etc.

A further advantage of the proposed locking device resides in the provision of means for adjusting the rudder control surface to counteract the propeller torque and cross winds. In cross-country flights, or trips of long duration, the rudder may be so set and locked in position that a direct course may be maintained, in spite of the direction and velocity of the wind, without the usual strain on the pilot caused by constant application of pressure of his foot against the rudder bar.

It is also proposed to provide a stirrup on the side of the rudder bar so constructed and arranged that the pilot may lock or unlock, set or operate freely the rudder bar with either foot by either the pressure of the foot on the bar or a pull against the stirrup.

With the foregoing and other objects in view, which will appear as the description proceeds, the invention consists in a combination of parts hereinafter described and claimed, it being understood that changes in the precise embodiment herein described may be made without departing from the spirit of the invention illustrated in the attached drawings in which,

Figure 1 is a plan view of the rudder bar provided with the locking and releasing mechanism.

Figure 2 is a section taken along line 2—2 of Figure 3.

Figure 3 is a section taken along line 3—3 of Figure 2.

Figure 4 is a sectional view of the stirrup on the line 4—4 of Fig. 1.

Figure 5 is a detail view of the stirrup and its relation to the rudder bar.

Figure 6 is a plan view of the rudder bars both front and rear, and the connecting means between same for use in dual control type of aircraft.

Figure 7 is a detail view of the connecting means between the stirrups of the front and rear rudder bars.

The control bar 1 as a whole is free to rotate on the spindle 7. Clutch levers 8 and 15 are provided with a clearance at each outer end of the control bar 1, when the teeth 10 on the clutch levers 8 and 15 are engaged with those of the ratchet or clutch member 11, which is mounted on base plate 12 and rigidly held by screws 13. The ratchet 11, being stationary, is provided with a centrally located square recess 14 through which the spindle 7 extends. The spindle 7 is so shaped that it snugly fits the recess 14 and is stationary at all times with relation to the base plate 12.

The clutch lever 8 is provided with a pin 16 inserted therein and riveted over on one end. The clutch lever 15 is provided with an elongated slot 17 through which pin 18 projects, causing clutch levers 8 and 15 to move together in either direction with relation to each other. Levers 8 and 15 are provided with lugs 18 to receive the opposite ends of a tension spring 19.

A stirrup 20 is provided near either end of the rudder bar 1, and is fulcrumed on brackets 21 by screws 22 and is adapted to engage clutch levers 8 and 15 at a point 23.

When the pilot's feet are free of the control bar 1, the tension spring 19 causes the teeth 10 of both clutch levers 8 and 15 to engage the ratchet or clutch member 11, thereby locking the control bar 1 to the clutch 11 and base plate 12. In order to disengage this locking means, it is only necessary to apply pressure against either lever 8 or 15 at a point 24, thereby causing the levers 8 and 15 which are fulcrumed on studs 9 and held there by nuts 32,

to disengage the clutch 11 until all clearance between clutch levers and control bar at the outer end of the control bar 1 is taken up, and clutch levers 8 and 15 are moved against the control bar 1 direct. The control bar 1 is then free to be operated in either direction, forward or backward.

By means of this arrangement it is possible to operate with one foot the mechanism to disengage the locking means and also to operate the control bar 1. This is made possible by the provision of the pin 16 which is fixed at one end of the clutch lever 8 and moves in the slot 17 in the clutch lever 15, thereby causing both clutch levers to move in relation to each other when either clutch lever is depressed in a forward direction.

Stirrup 20 is fulcrumed on brackets 21 by screws 22 and engages the clutch levers 8 and 15 at a point 23, and provides a means of unlocking the clutch 11 by pulling back on the stirrup 20 of the control bar 1 with the toe portion of either foot.

As shown in Figure 6 the rudder control bar may be applied to the dual control type of aircraft by providing a control bar in both cockpits identical with that heretofore described and connecting the ends of the control bars by means of a cable 30 which in turn is adapted to be attached to the rudder of the aircraft. Furthermore the clutch levers of the two control bars are connected to each other by means of a rigid member 31 such as a metallic rod. Thus when the one control bar is operated or locked or unlocked the other control bar is accordingly actuated in the same manner.

It will be clearly seen that there is thus provided a rudder bar capable of being operated by either foot by exerting either a pulling or pushing energy therewith. There has also been provided a rudder bar capable of being set in any desired position and which will automatically lock itself in set position upon the release of the pilot's foot from the rudder bar. There has further been provided a rudder bar with a stirrup by which the rudder bar may be operated by means of the exertion of a pull by the pilot with the toe portion of either foot on the stirrup, said operation obtaining the same results as a pressure upon the rudder bar proper at a point 24. Furthermore in the dual control type of aircraft the control bar may be set and locked in any desired position and the rudder operated by the application of pressure on the clutch lever or pull on the stirrup of either control bar by either foot.

While I have illustrated and described the foregoing precise and preferred embodiment of my invention, it is apparent that changes in the details of construction and operation thereof may occur, and it is therefore not my intention to confine my invention to such

an embodiment, but to limit the same only to such an extent that it will fall within the scope of the broadest interpretation of the appended claims.

Having thus described my invention, I claim:

1. For use in an aircraft, a rudder bar, means for automatically locking said rudder bar comprising a stationary ratchet, opposing clutch levers, each pivotally mounted on said rudder bar, and means for interconnecting said clutch levers, said clutch levers being free to actuate while thus connected for engaging or disengaging said ratchet, when pressure is applied to one of the said clutch levers.

2. In combination with a pivotally mounted rudder bar, locking and releasing means embodying a stationary clutch member, movable clutch members to cooperate therewith mounted on the rudder bar, a plurality of foot levers, and means to interconnect said foot levers so that each of them is adapted to release both of the movable clutch members.

3. In a rudder control bar for use more particularly in aircraft, means for automatically locking said rudder bar comprising a ratchet, opposing clutch levers pivotally mounted on said rudder bar and operated in relation to each other by means connecting said clutch levers, said clutch levers being free to actuate while thus connected for engaging or disengaging said ratchet, when pressure is applied to one or both clutch levers, and a stirrup pivotally mounted at each end of said rudder control bar and provided with an extension adapted to engage one of said clutch levers and disengage both said levers from said ratchet when a pull is exerted on said stirrup.

4. For use in an aircraft, a rudder bar, a base plate, a stationary ratchet mounted thereon, clutch levers on said rudder bar adapted to engage said ratchet member and resilient means for retaining same in locked engagement therewith, said clutch levers being connected at one end by means of a pin in one, riding in an elongated slot in the other, each of said levers being fulcrumed at a point substantially midway of its length.

5. For use in aircraft of the dual control type having a pair of rudder control bars for operating the rudder control mechanism of said aircraft, means comprising a ratchet and opposing clutch levers adapted to engage said ratchet, for automatically locking said control bars in any desired position, and means for releasing said automatic locking means and means for connecting said rudder bars to each other and to the rudder control mechanism of said aircraft, rigid members connecting the respective clutch levers of said control bars for the purpose of enabling the simultaneous engagement and

disengagement of said locking mechanism of each control bar and the operation of said rudder by the actuation of either control bar.

- 5 6. For use in an aircraft of the dual control type having a pair of rudder control bars for operating the rudder control mechanism of said aircraft, means comprising a ratchet and opposing clutch levers adapted
- 10 to engage said ratchet, for automatically locking said control bars in any desired position, and means for releasing said automatic locking means, and means for connecting said rudder bars to each other and
- 15 to the rudder control mechanism of said aircraft, rigid members connecting the respective clutch levers of said control bars for the purpose of enabling the simultaneous engagement and disengagement of said locking mechanism of each control bar and the
- 20 operation of said rudder by the actuation of either control bar, and a stirrup pivotally mounted at each end of each control bar and

provided with an extension adapted to automatically engage said clutch levers and disengage said clutch levers from said stationary ratchet when a pull is exerted on said stirrup, the stirrup of each control bar being so rigidly connected to that of the other that the operation of either stirrup will cause 25 the simultaneous operation of the other.

7. In combination with a pivotally mounted foot-operated control bar, a stationary ratchet member, opposing ratchet levers mounted on said bar and adapted to engage 30 said stationary ratchet member, resilient means for maintaining said levers in engagement with said ratchet member, a stirrup pivotally mounted at each end of said control bar and provided with an extension 35 adapted to engage its respective ratchet lever to release the control bar when a pull is exerted on said stirrup.

In testimony whereof I have affixed my signature.

ERNEST G. McCUALEY.
